(57) CLAIM

The ornamental design for a combined cookware pan and lid, as shown and described.

DESCRIPTION

FIG. 1 is a perspective view of a combined cookware pan and lid showing the new design;
FIG. 2 is a right-side view thereof;
FIG. 3 is a left-side view thereof;
FIG. 4 is a front view thereof;
FIG. 5 is a rear view thereof;
FIG. 6 is a top view thereof; and,
FIG. 7 is a bottom view thereof.

The broken lines shown in the figures depict portions of the combined cookware pan and lid that form no part of the claimed design. Further, the broken lines immediately adjacent the solid-line portions of the design form the boundary of the design, with the broken lines forming no part of the claimed design.
